US00D611802S

(12) United States Design Patent
Li

(10) Patent No.: US D611,802 S
(45) Date of Patent:  Mar. 16, 2010

(54) SUPPORT

(76) Inventor: Chin-Chu Li, 18F., No. 71, Sec. 2,
Dunhua S. Rd., Taipei 106 (TW)

() Term: 14 Years

(21) Appl. No.: 29/309,221

(22) Filed: Jul. 10, 2008

(51) LOC (9) Cl. 08-05

(52) U.S. Cl. D8/363

(58) Field of Classification Search D6/454;
D14/452, 432, 447-448, 451, 457; 248/126,
248/286.1, 274.1; D8/363

See application file for complete search history.

(57) CLAIM

The ornamental design for a “support,” as shown and described.

DESCRIPTION

FIG. 1 is a perspective view of a “support” showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portion of the figure drawings is included to show unclaimed subject matter only and forms no part of the claimed design.

1 Claim, 6 Drawing Sheets

FIG. 1

FIG. 3

FIG. 4
